Primary Examiner — Natasha Vujcic

(57) **CLAIM**

The ornamental design for a base for decorative lights, as shown and described.

DESCRIPTION

FIG. 1 is a top perspective view of a base for decorative lights design showing my new design;

FIG. 2 is a bottom perspective view of the base for decorative lights design showing my new design;

FIG. 3 is a front view thereof;

FIG. 4 is a rear view of thereof;

FIG. 5 is a left view of thereof;

FIG. 6 is a right view of thereof;

FIG. 7 is a top view of thereof;

FIG. 8 is a bottom view of thereof;

FIG. 9 is an exploded perspective view of the base for decorative lights design showing my new design;

FIG. 10 is an enlarged view of the selected portion "10" in FIG. 1;

FIG. 11 is an enlarged view of the selected portion "11" in FIG. 2; and,

FIG. 12 is an enlarged view of the selected portion "12" in FIG. 2.

Any shading and cross-hatching are not features of the design but are utilized to illustrate the surface contours of the base for decorative lights design in the drawings. The broken lines depict portions of the base for decorative lights design, and form no part of the claimed design.

The dot-dash broken lines in the drawings represent the boundaries of the enlarged portions which form no part of the claimed design.

1 Claim, 12 Drawing Sheets
